UNITED STATES PATENT OFFICE.

HERBERT G. SMITH, OF CLAYSVILLE, PENNSYLVANIA.

EARTH-DRILL.

SPECIFICATION forming part of Letters Patent No. 508,187, dated November 7, 1893.

Application filed April 27, 1893. Serial No. 472,123. (No model.)

To all whom it may concern:

Be it known that I, HERBERT G. SMITH, a citizen of the United States, residing at Claysville, in the county of Washington and State 5 of Pennsylvania, have invented certain new and useful Improvements in Earth-Drills; and I do hereby declare the following to be a full, clear, and exact description of the invention, such as will enable others skilled in the art to 10 to which it appertains to make and use the same.

This invention relates to improvements in the mechanism of earth drills and its objects are, first, to lengthen the reach of the temper screw relatively to the fixed limits of operation 15 of the walking beam; secondly, to avoid kinking or bending the temper screw on withdrawal from the bore; thirdly, to better distribute the weight of the temper screw and its counterbalance, and so reduce the tendency 20 of the temper screw to jump at the beginning of operation; fourthly, to give the lifting rope a direct vertical pull upon the temper screw, to avoid side draft and bending of the screw; fifthly, to keep the lifting 25 rope from interference or entanglement with the casing, mechanism or implements used in the operation of drilling; sixthly, to better protect the pulley over which the lifting rope passes from accidental breakage or injury; 30 seventhly, to improve the means for adjustably holding the temper screw within its support; eighthly, to prevent undesired rotation of the drill cable upon its supports; ninthly, to improve the bearings of the rotatable supports 35 of the drill bit, and tenthly, to improve the construction and operation of the cable clamps.

In the accompanying drawings, wherein like numerals represent like parts, Figure 1 40 is a side elevation of my improved drill; Fig. 2, a rear elevation of the same; Fig. 3, a vertical, longitudinal, sectional view on the line $w-w$ of the second figure, looking in the direction of the arrow; Fig. 4, a horizontal, sectional view on the line $x-x$ of the first figure, showing the detachable, threaded linings through which the temper screw works; Fig. 45 5, a horizontal, sectional view on the line $y-y$ of the first figure, showing the roller bearings

at the base of the screw; Fig. 6, a horizontal, 50 sectional view on the line $z-z$ of the first figure, showing the clamping device for holding the cable.

The drill bit 2 is attached to the drill cable 3 in the usual manner. The cable clamps 4 55 and 5 are wider at top than at the bottom. The clamp 4 has a hook, 6, preferably swiveled, projected from its edge near the lower end, engaging with an eye, 7, correspondingly projected from the proximate edge of the 60 other clamp, thus hinging the clamps and preventing their separation when loosened from the cable. The clamp 5 has a pivoted screw 8; projected from its other edge and fitting between a pair of arms, 9, projected from the 65 proximate edge of the other clamp. Working upon the screw is a lever, 10, having a long, threaded shank, 11, bearing against the arms, and by means of this lever the clamps are fastened to and unfastened from the cable. 70 Each clamp has a hook, 12, bent outward and downward from the center of its upper edge, and these hooks engage with a pair of links, 13, that connect the cable with the supporting and operating mechanism. The cable is 75 suitably thickened along and around the area of clamping, to enable the clamps to hold to it firmly.

The drill cable is supported directly from the temper screw 14, which has a broad, 80 annular foot, 15, to serve as a base for the cable support, which consists of a yoke, 16, bearing the aforesaid links 13, and turning upon the shank of the temper screw. This yoke rests upon a set of thin rollers, 17, preferably four 85 in number, the inner faces of which rest, in single file, against the shank of the temper screw. To keep these otherwise loose rollers from falling outwardly from their vertical positions, the foot of the temper screw has a vertically rising flange, 18, encircling it, and there is interposed between the yoke and the rollers a deeply flanged washer, 19, which helps to confine the rollers to their respective places, edge to edge and in vertical position, 90 and by means of shoulders, 20, on its upper edge, engaging with recesses, 21, in the lower edge of the yoke, the yoke and washer inter-

lock, so as to turn together upon the rollers. The substitution of these rollers for ball bearings makes the work of rotation easier for the operator.

5 When it is desired that the drill cable shall not rotate or shall rotate at a controlled speed only, a thumb screw, 22, working through the yoke and bearing upon the temper screw, or, if preferred, upon a bushing, which may be 10 fitted into the space indicated at 23, fitted between the yoke and the shank of the temper screw, clamps the yoke fast upon the shank, or serves as a friction brake to regulate the speed of rotation.

15 The temper screw 14 is connected to and supported from the walking beam 24 by a pair of reins, 25, provided at their lower ends with a pair of boxes, 26, containing or supporting adjusting devices for the screw. One of these 20 devices is a clevis, 27, surrounding one of the boxes and pivoted to the other, and provided with a set screw, 28, through the head of the clevis, which screw bears against the outer wall of the proximate box and so clamps the temper 25 screw between the boxes. By facing the wall of the box with a relatively thick bearing plate, 29, a slight loosening of the screw will allow it to be lifted upward and into a recess, 30, above the plate, so that the boxes can be 30 quickly unclamped and the temper screw moved up or down. Each interior wall of the box is fitted with a detachable, threaded, half circular lining, 31, suitably keyed in place, so that when these linings become too much 35 worn from the friction of the temper screw they may be removed and replaced by new linings without renewing the boxes. Keyed to the temper screw, above the aforementioned yoke, is the accustomed double han- 40 dled lever, 32, for working the temper screw up or down through the boxes when they are clamped.

The reins 25 extend above the head of the temper screw, and one of them is formed into 45 a shoulder, 33, at the top, containing a slot, 34, to accommodate a pulley, 35, which the shoulder thus substantially protects from injury. The lifting rope 36 passes from the head of the temper screw over this pulley, 50 insuring a straight vertical pull in raising the temper screw, avoiding the waste of power and the bending of the screw in rais- 55 ing the screw by an oblique pull. The reins pass through a longitudinal slot, 37, in the walking beam, which accommodates their journal 39 in the boxes 40, or otherwise on the upper surface of the beam. By passing the reins up into the beam, and supporting the apparatus from the upper instead of the 60 lower face of the beam, there is a gain of length in the temper screw, enabling the drill to go deeper into the bore before readjusting the motor machinery or making other arrangements for deeper boring.

65 By the described method of supporting the

apparatus, the lifting rope 36 is carried along the top of the walking beam out of the way of entanglement; also, the apparatus is prevented from twisting or turning and so getting kinked or bent; the weight of the apparatus, including the usual balance at the end of the lifting rope, is better distributed upon the walking beam, and the operation of the drill, as a whole, materially steadied.

It is to be understood that merely mechanical details in the construction of this earth drill may be varied as the ordinary judgment and experience of the constructor or operator may suggest, without departing from the substance or spirit of the invention. This explanation has especial reference to the cable clamp attachments, the yoke supporting the cable, the friction bearings beneath the yoke, the clevis attachments, the interior construction of the boxes inclosing the temper screw, 85 and the rein supports on the upper surface of the walking beam.

Having thus described my invention, I claim the following:

1. The combination, in an earth drill, of the walking beam having the vertical, longitudinal slot near one end thereof; the pair of reins, supported by their journal upon, and depending from the beam and passing through the beam slot; the pulley, mounted vertically in the upper part of one of the reins; the pair of boxes formed at the bottom of the reins, having concave, semicircular, screw-threaded inner faces; the clevis, pivoted to one box and loosely encircling the other, and having a set screw fitted in and through it, opposite the pivoted end or section; the temper screw between the reins, having the lifting rope in the head thereof, passing over the aforesaid pulley, and further having the fixed hand lever below the aforesaid boxes, and the annular foot with vertically rising flange; the rollers, placed around the shank of the temper screw, upon the annular foot and within the flange; the yoke loosely mounted and turning upon the temper screw and supported upon the aforesaid rollers, and the pair of cable clamps, linked to and below said yoke, and having projected from the vertical edges of one clamp the hook and the pivot screw, and, from the vertical edges of the other, the eye engaged with the hook and the arms embracing the pivot screw—the said pivot screw having thereon a lever with a threaded shank bearing against the arms aforementioned; the whole constructed and arranged substantially as and for the purposes described.

2. The combination in an earth drill of the walking beam having the vertical longitudinal slot near one end thereof; a pair of reins, supported by their journal upon, and depending from the beam and passing through the beam slot; the pulley, mounted vertically in the upper part of one of the reins; the tem- 130

per screw between the reins, having in its head the lifting rope, passing over the aforesaid pulley, and further provided with a fixed hand lever, below the aforesaid reins, and 5 with the annular foot; and the slevin, pivoted to the lower part of one rein and loosely encircling the other, and having a set screw fitted in and through it, opposite the pivoted

end or section of said clevis; all substantially as described, for the purposes set forth.

In testimony whereof I affix my signature in presence of two witnesses.

HERBERT G. SMITH.
